UNITED STATES PATENT OFFICE.

RICHARD O. BLANK, OF READFIELD, WISCONSIN.

CUSPIDOR-CARRIER.

1,239,868.

Specification of Letters Patent. Patented Sept. 11, 1917.

Application filed May 16, 1917. Serial No. 169,068.

To all whom it may concern:

Be it known that I, RICHARD O. BLANK, a citizen of the United States, residing at Readfield, in the county of Waupaca, State 5 of Wisconsin, have invented a new and useful Cuspidor-Carrier; and I do hereby declare the following to be a full, clear, and exact description of the invention, such as will enable others skilled in the art to which 10 it appertains to make and use the same.

The invention relates to improvements in cuspidor carriers.

One of its objects is to provide a simple and inexpensive device of this character for 15 gripping the funnel or mouth of a cuspidor to permit the cuspidor to be carried without contact with the hands.

Another object of the invention is the provision of a cuspidor carrier which is 20 capable of completely covering the funnel of the cuspidor that the nostrils may not be subjected to the scents arising therefrom.

Other objects will appear in the detailed 25 description which follows.

It is to be understood that the invention is not to be confined to the exact forms of 30 construction herein disclosed, the right being reserved to make any changes or alterations falling within the scope of what is claimed.

In the drawings:

Figure 1 is an elevation of one embodiment of the invention.

Fig. 2 is a section on the line 2—2 of 35 Fig. 1.

Fig. 3 is a section on the line 3—3 of Fig. 1.

Fig. 4 is an elevation of another embodiment of the invention.

Fig. 5 is a section on the line 5—5 of 40 Fig. 4.

Fig. 6 is a section on the line 6—6 of Fig. 4.

Fig. 7 is a perspective view of still another form of the invention.

Referring to the drawings, and particularly Fig. 1, 1 designates a pair of covered grips which are designed to grasp the funnel or mouth of a cuspidor. These grips 50 are semi-circular in plan and when joined together form a circular disk with a depending flange 2 having at its lower end an inturned annular flange 3. This annular flange 3 provides the means for gripping the funnel of a cuspidor. Adjacent to the 55 straight edges where the grips 1 adjoin

each other, suitable carrying members are attached. These carrying members comprise rods 4 and 5 which are rectangular in cross-section and are pivotally united near 60 their lower extremities by the pivot pins 6. Below the pivotal connection, each rod 5 blends into the enlargement 7, the latter terminating in an angled end 8 by means of which the rod 5 is attached to the top of 65 the grip 1 with the aid of suitable rivets 9. Each rod 4 has an enlargement 10 below the pivot pin 6. The extremity 11 of the enlargement 10, however, is not turned at an angle but remains straight, being secured to the 70 flange 2 by means of suitable rivets 12. Both enlargements 10 are provided with stationary pins 13 and these pins move in circular slots 14 formed in the enlargements 7 concentric with the pivot pins 6. The rods 4 and 5 75 are assembled in pairs, each pair comprising a rod 4 and a rod 5. Above the pivot pins 6 the two pairs of rods bend in toward each other for a portion of their length and then bend out running parallel to each other 80 for the remainder of their length. At the top a suitable handle 15 is secured between the rod 4 of one pair and the rod 5 of the other pair and an identical handle is similarly secured between the remaining rods 85 4 and 5, the two handles lying against each other when the grips 1 are in contact.

It will be observed that each grip has connected to it a rod 4 and a rod 5 united at their tops by a handle 15, the rod 5 being connected 90 on top of the grip by the angled end 8 and the rod 4 being connected on the flange 2 of the grip by the extremity 11. The operation of the device is obvious. Separating the two handles 15 will result in separating 95 grips 1, so that they may be placed over the mouth or funnel of the cuspidor. Bringing the two handles 15 together then brings the two grips together, when the annular flange 3 will engage the under edge of the funnel 100 of the cuspidor, permitting the latter to be carried without contact of the hands. The grips 1 being covered will, of course, cover the funnel of the cuspidor and protect the person carrying the latter from obnoxious 105 odors. The pins 13 operate in conjunction with the slots 14 to limit the distance to which the grips 1 can be separated.

In Figs. 4, 5 and 6, there is shown another form of the invention. In this form the 110 grips constitute a pair of semi-elliptical bands 20 and the carrying members com-

prising the rods 21 and 22. The rods are assembled in pairs by pivot pins 23, each pair constituting a rod 21 and a rod 22. Below the pivot pins 23, the bands 20 are 5 connected to the rods 21 and 22, the ends of one band 20 being connected to the lower extremities of the rods 21 and the other band 20 being similarly connected to the lower extremities of the rods 22. The rods 10 21 and 22 are rectangular in cross section and below the pivot pins 23 are enlarged. On these enlarged portions, the rods 22 are provided with stationary pins 25 which move in circular slots 26 formed in the 15 enlarged portions of rods 21. The slots 26 are concentric with the pivot pins 23 and the pins 25 are provided with heads which overlie these slots, the object of these headed pins being to prevent the rods 21 and 22 20 from springing or bending away from each other at their lower extremities, thus keeping the bands 20 in their normal positions with respect to each other. Above the pivot pins 23, the two pairs of rods 21 and 22 25 bend in toward each other and then bend outward, running parallel for the rest of their length. At the upper extremities, handles 24 connect the rods together, one handle connecting the rods 22 and the other 30 handle the rods 21.

This form of the invention operates as does that form shown in Fig. 1. Separating the two handles 24 operates to separate the two bands 20 which may then be placed 35 over the mouth or funnel of a cuspidor. On being brought together as a result of having the handles 24 brought together, the bands 20 will engage under the edge of the funnel of a cuspidor, whereupon the latter may be 40 convenient to carry. The object of this form is to cheapen the construction of the device and the bands 20 are made elliptical to enable them to engage the funnel of a cuspidor without interference from the carrying means comprising the rods 21 and 22. The minor axis of the ellipse which the bands 20 form is designed to be less than the diameter of the funnel of the cuspidor to be carried, while the major axis is 45 designed to be greater than the funnel diameter. The carrying rods 21 and 22 being connected at points through which the major axis of the ellipse passes, do not, therefore, come in contact with the edges of the cuspidor funnel but permit the latter to be 50 grasped by the bands 20 at points through which the minor axis of the ellipse passes.

In Fig. 7, there is shown still another form of the invention. This form is very 55 simple in construction and is designed for carrying small cuspidors. It comprises the round rods 30 and 31 both of which are substantially straight for the greater portion of their length. At their lower extremities 60 they have the semi-circular bends 32 and 33

formed on them respectively. These semi-circular bends do not lie in the same plane with the lengths of the rods but in a plane at right angles thereto. The semi-circular bend 32 terminates in an eye 34 and the 70 bend 33 terminates in an eye 35 which loosely engages the eye 34 and connects the two bends together. On the upper extremity of the rod 30 an eye 36 is formed which lies in the same plane as the rod. On the upper 75 extremity of the rod 31 a similar eye 37 is formed but this eye is turned at right angles to the length of the rod and loosely engages the eye 36 to connect the two rods together.

The manner in which the device in Fig. 7 80 may be utilized is apparent. The operation of separating the rods 30 and 31 will enable the semi-circular bends 32 and 33 to be placed around the funnel of the cuspidor and the latter may be carried by the device 85 after the rods 30 and 31 are brought together.

What is claimed is:

1. In a cuspidor carrier, a pair of gripping members adapted to grasp the funnel 90 of a cuspidor, each gripping member comprising a semi-circular disk having a depending flange and an annular flange in-turned from the lower edge of the depending flange, and carrying members connected 95 with the grips, the carrying members being conjoined with means whereby the grips may be separated and brought together to effect their attachment to the funnel of a cuspidor.

2. In a cuspidor carrier, a pair of gripping members adapted to grasp the funnel 100 of a cuspidor, each gripping member comprising a semi-circular disk having a depending flange and an annular flange in-turned from the lower edge of the depending flange, carrying members connected with the grips, the carrying members being assembled in pairs with those of each pair pivotally connected together, and handles 105 connected with the carrying members at the ends remote from the ends connected with the gripping members, one handle connecting the carrying members attached to one grip and the other handle connecting those 110 attached to the other grip, the two handles being adapted for movement toward and from each other, whereby the carrying members are oscillated on their pivotal connections and the gripping members separated 115 and brought together.

3. In a cuspidor carrier, a pair of opposing gripping members adapted to grasp the funnel of a cuspidor, said gripping members consisting of semi-circular disks, 125 which, when their adjacent edges are in contact, form a circular cover for covering the top of the cuspidor, each gripping member having a depending flange and an annular flange in-turned from the lower edge of 130

the depending flange to engage the perimeter of the cuspidor below its funnel, carrying members connected with the grips, the carrying members being assembled in pairs 5 with those of each pair pivotally connected together, handles connected with the carrying members at the ends remote from the ends connected with the gripping members, one handle connecting the carrying members 10 attached to one grip and the other handle connecting those attached to the other grip, the handles being adapted for movement toward and from each other, whereby the carrying members are oscillated on their 15 pivotal connections and the gripping mem-

bers separated and brought together, the lower ends of each pair of carrying members between their attachments to the grips and their pivotal connections having enlargements, one enlargement of one carrying member of each pair having a slot with closed ends, and a pin carried by the adjacent enlargement and engaging said slot. 20

In testimony whereof I have signed my name to this specification in the presence of 25 two subscribing witnesses.

RICHARD O. BLANK.
